UNITED STATES PATENT OFFICE.

JOSEPH H. TAVENNER, OF HEBRON, OHIO.

DESIGN FOR A TRAFFIC-SIGN.

52,416.

Specification for Design. Patented Sept. 10, 1918.

Application filed December 1, 1916. Serial No. 134,530. Term of patent 14 years.

To all whom it may concern:

Be it known that I, JOSEPH H. TAVENNER, a citizen of the United States, residing at Hebron, in the county of Licking and State of Ohio, have invented a new, original, and ornamental Design for Traffic-Signs, of which the following is a specification, reference being had to the accompanying drawing, forming part thereof.

The figure is a perspective view of a traffic sign, showing my new design.

I claim:

The ornamental design for a traffic sign, as shown.

JOSEPH H. TAVENNER.

Witnesses:

C. C. SHEPHERD,
A. L. PHELPS.
